UNITED STATES PATENT OFFICE.

EUGENE W. WALSH, OF NEW YORK, N. Y.

TELEPHONE-BOOTH DOOR.

1,089,449.

Specification of Letters Patent. Patented Mar. 10, 1914.

Application filed September 12, 1913. Serial No. 789,460.

To all whom it may concern:

Be it known that I, EUGENE W. WALSH, a citizen of the United States, and a resident of New York, in the county and State of the same name, have invented certain new and useful Improvements in Telephone-Booth Doors, of which the following is a specification.

This invention relates to doors and particularly to that class used in connection with telephone booths.

The objects of the invention are, to provide doors that can be opened or closed easily and noiselessly from either side, without danger of catching or pinching the fingers or garments of the operator, which will fold compactly upon themselves when in an opened position and which are substantially sound proof when closed. These and other objects, such as economy of construction, neatness of appearance and simplicity of action, are attained by the novel construction and combination of parts hereinafter described and shown in the accompanying drawings, forming part of this specification, and in which:

Figure 1 is a front elevation of a telephone booth in outline having a door made in accordance with the invention, the same being shown in a closed position. Fig. 2 is a similar view of the same, but showing the door open. Fig. 3 is a transverse sectional view of the booth taken on line 3--3 of Fig. 1, the same being in a plane with the top of the door. Fig. 4 is a similar view, taken on line 4--4 of Fig. 2. Fig. 5 is an enlarged plan view of the front edge of the door, as closed and its casing. Fig. 6 is a partial plan view showing the joint between portions of the door, the same being in a closed position. Fig. 7 is a similar plan view of the same, but showing the door open or folded. Fig. 8 is a sectional view of the equalizing means, taken on line 8--8 of Fig. 6. Fig. 9 is a transverse sectional view of the joint bar and attachment, taken on line 9--9 of Fig. 1, and, Fig. 10 is another plan view showing a modified form of center joint construction.

The booth may be of any preferred construction with respect to the side walls 10 and 11, rear wall 12, ceiling 13 and base 14, the latter being provided with a raised flooring having no threshold raised above the level of its surface. At the front of the booth a narrow jamb 16 is secured to the side

wall 10, the edge of the jamb next the door having a bevel 17, of approximately twenty degrees. At the opposite side of the door is a jamb 18 connected with the side wall 11, and having its exposed edge formed with a concave surface 19, the radius of which is taken at a definite point in front of and toward the center of the door. Secured on the inner side of the jamb 18 is a strip 20, one edge of which overlaps the extreme, thin edge of the jamb.

The door is comprised of two main elements 22 and 23, the former of which is secured by hinges 24 to the jamb 16, but in such manner as to avoid tight contact between its beveled edge 25 and the corresponding bevel 17 of the jamb. The hinges 24 are arranged inside the booth, the pivot being spaced from the edge of the door a definite distance as shown. The outer edge of the door element 23 is curved to agree with the concave surface 19 but so arranged as to be slightly clear of it when the door is fully closed, the narrow opening being practically imperceptible from the front or outer side and covered at the inside by the strip 20. These door elements 22 and 23 have their adjacent edges, formed with interiorly curved recessed outer corners 26 and 27, and beveled surfaces on the opposite inner corners. Within the concave corners 26 and 27 is a vertically disposed bar 28 of semi-circular cross section, having a flat face 29 extending beyond the surface of the main elements of the door in and between which the main portion is surrounded. The elements 22 and 23 are connected together and with the bar 28 by hinges 30 disposed on the outer side of the door, the pivot of the hinges being located at the center of the semi-circular bar so that the door elements may rotate about it, the hinge being secured to the bar by means of screw eyes 31 which engage with the projecting ends of the hinge pins. On the top of both door elements, near the bar 28, are pivotally secured the ends of links 32, their opposite free ends being crossed one over the other and provided with an opening to receive the stem 33 of the equalizing slide 34 which latter is mounted to slide freely on the pin 35, rigidly secured at one end in the center of the bar 28 and extending oppositely to and at a right angle with the face 29. Thus no matter what the position the door elements may be the joint between them is so covered as to protect the

fingers or garments of a person using the booth from injury therein.

In order to cause the door to move properly and fold closely out of the way of the user, and by a single pushing movement exerted preferably against the bar 28, a rod 38 is pivotally connected to a bracket 39 attached to the inner side of the door element 23, midway of its width, its opposite end being similarly engaged with another like bracket 40 attached to the rear wall 12, substantially central and near the ceiling 13.

In the modification shown in Fig. 10 the door elements 22 and 23 are of the same construction, but have between them a bar formed with two curved surfaces 50 and 51 respectively filling the concave edges 26 and 27; the radii of these curves is taken from two points which correspond with the pin centers 52 and 53 of the double hinge, the leaves 54 and 55 of which are secured to the door elements, the center part of the hinge between the pivotal points being secured to the bar.

From the foregoing it will be understood that the operative parts which project into the booth are at the extreme top, where they are out of the way of a person using the same and hence offer no impediment. It is also noticeable that the vertical bar, by reason of its location and peculiar action, at all times extends outwardly beyond the joint between the door elements thereby absolutely preventing the intrusion of anything therein.

I claim:

1. A folding door comprising two main elements, the inner of which hingedly engages with a jamb at one edge and with the outer element at the opposite edge, a supplementary element disposed between the said main elements, an equalizing means combined with said door elements and means for rod controlling the movement of the outer element.
2. A folding door comprising two main elements relatively wide and narrow, the latter being hingedly engaged with a support in such manner as to swing away from it when operated, pivotal connections between said elements at their adjacent edges, a vertical bar loosely confined within the joint between the adjacent edges of said elements, preventing the intrusion of objects therebetween and means for maintaining said bar in operative position relative to the joint, irrespective of the position of said door elements.

3. A folding door comprising two main elements of unequal width, the narrower being hingedly engaged with a jamb, curved recesses formed in the adjacent corners of said elements, a bar having a semi-cylindrical cross section disposed in said recesses, said bar having a flat outer side, hinge connections between said elements, said hinged connections pivotally engaging said bar on the flat side thereof, and means combined with said elements and said bar whereby the flat side is held at an angle uniform with each of said main elements, irrespective of their position.

4. A folding door comprising relatively wide and narrow elements, said narrow elements having an outwardly beveled outer edge, a jamb suited to the bevel of said narrow element, hinges on the inner side thereof and connecting therebetween, said hinges having their pivotal point adjacent to said jamb and definitely spaced rearward from the edge thereof, a second jamb at the opposite side of the door, said second jamb being formed with a concave recess along its front edge, the wider element being suited thereto, a strip interior of said second jamb extending past the inner edge thereof, hinges between said door elements, and means combined therewith preventing the entrance of objects to the joint therebetween and from either side thereof.

5. A folding door comprising two main elements, the inner of which is hingedly engaged with a jamb at one edge and with the outer element at the opposite edge, an equalizing means combined with said elements and their joint therebetween, and a radius rod controlling the movement of the said outer element.

6. A folding door comprising three elements, the central element being substantially D shaped in cross section and partially inclosed by the outer elements, hinges engaging said outer elements and confining the said central element therebetween and means whereby the flat portion of said central element is caused to move in planes parallel to its original position when the door is operated.

In testimony whereof I have signed my name to this specification in the presence of two subscribing witnesses.

EUGENE W. WALSH.
